(57) **CLAIM**

The ornamental design for an ice scraper instrument, as shown and described.

DESCRIPTION

FIG. 1 is a perspective view of an ice scraper instrument showing my new design;

FIG. 2 is a top perspective view thereof;

FIG. 3 is a side elevational view thereof;

FIG. 4 is a side elevational view thereof, opposite of FIG. 3;

FIG. 5 is a side perspective view of the tip portion of the ice scraper instrument shown fragmented for clarity of disclosure;

FIG. 6 is a side view thereof;

FIG. 7 is a bottom perspective view of the ice scraper instrument thereof;

FIG. 8 is a top perspective view thereof;

FIG. 9 is a perspective view thereof;

FIG. 10 is another perspective view thereof;

FIG. 11 is a perspective view of a second embodiment of an ice scraper instrument showing my new design;

FIG. 12 is another perspective view thereof;

FIG. 13 is side elevational view thereof;

FIG. 14 is a side elevational view thereof, opposite of FIG. 13;

FIG. 15 is a bottom perspective view thereof; and,

FIG. 16 is a top perspective view thereof.

The broken lines shown in the drawings are for illustrative purposes only and form no part of the claimed design.
